CLAIM

We claim the ornamental design for a bottle, as shown and described.

DESCRIPTION

FIG. 1 is a top perspective view of a bottle showing the new design;

FIG. 2 is a front elevation view thereof, with the back, left, and right elevation views being identical to the front elevation view shown in FIG. 2;

FIG. 3 is a top plan view thereof;

FIG. 4 is a bottom plan view thereof;

FIG. 5 is top perspective view thereof, with the cap exploded from the container;

FIG. 6 is a cross-sectional view taken along line 6-6 in FIG. 5; and

FIG. 7 is a front elevation view thereof, with the cap exploded from the container, where the back, left, and right elevation views being identical to the front elevation view shown in FIG. 7;

FIG. 8 is a top plan view thereof, with the cap exploded from the container; and,

FIG. 9 is a bottom plan view thereof, with the cap exploded from the container.

The evenly spaced broken lines and the areas within the broken lines depict environmental subject matter that forms no part of the claimed design. The dot-dash broken lines shown in FIGS. 5-7 demonstrate the manner of assembly and form no part of the claimed design.

1 Claim, 7 Drawing Sheets
